UNITED STATES PATENT OFFICE.

FRANK C. KIRKPATRICK, OF TUPELO, MISSISSIPPI.

CULTIVATOR.

1,273,621.

Specification of Letters Patent. Patented July 23, 1918.

Application filed October 31, 1917. Serial No. 199,521.

To all whom it may concern:

Be it known that I, FRANK C. KIRKPATRICK, a citizen of the United States, residing at Tupelo, in the county of Lee and State of Mississippi, have invented certain new and useful Improvements in Cultivators, of which the following is a specification.

This invention relates to cultivators, and particularly to the blades or shovels thereof, aiming primarily to simplify and improve the construction and operation of devices of this character, as well as to increase their efficiency.

A further object of the invention is to provide an improved cultivator blade standard and blade, so constructed as to permit of blades of various sizes being quickly and easily applied to the standard, and rest upon the latter so as to prevent accidental detachment of the same.

A further object of the invention is to provide a blade standard and blade of extremely simple and inexpensive construction, which embodies mechanism of simple construction and of easy operation, and which will prove thoroughly practical and efficient in use.

With these objects in view, together with others which will appear as the description proceeds, the invention resides in the novel formation, combination, and arrangement of parts, all as will be described, illustrated in the drawings, and particularly pointed out in the claims.

35 In the drawings:—

Figure 1 is a vertical sectional view taken through a blade and standard of my invention, the view showing the blade properly assembled upon the standard,

40 Fig. 2 is a rear elevation of the device shown in Fig. 1,

Fig. 3 is a view similar to Fig. 1, and showing the blade detached therefrom, and

45 Fig. 4 is a rear elevation of the blade used in carrying out the invention.

Referring now more particularly to the drawings 5 indicates a blade or shovel supporting standard, and which blade is secured to a cultivator frame in any preferred manner. This standard is curved forwardly ad-

jacent its lower end, and is provided with a pair of rearwardly projecting longitudinally disposed ribs 6. The forward face of the standard 5 is provided with a pair of spaced openings or apertures 7, the latter being disposed between the ribs 6. 55

The blade or shovel of my invention is indicated generally at 8, and may be of any preferred size or shape, and is preferably formed of metal. This blade is provided upon its rear face with a pair of longitudinally alined lugs 9, each of which is bent angularly and upwardly at its outer end as at 10. The distance between the under faces of the angular portions 10 of the lugs and the rear face of the blade or shovel 8 is substantially equal to the thickness of the standard adjacent the openings 7. When the blade has been applied to the forward face of the standard 5 and at the lower edge thereof, 65 the lugs 9 will enter their respective openings, and upward sliding movement delivered to the blade or shovel will cause the hooked or angular portions of the lugs to engage behind the metal defining the edges 65 of the openings. When the blade 8 is moved downwardly, the hooked or angular portions 10 of the lugs will pass from behind the edges of the openings, whereupon the blade 70 may be readily withdrawn from the standard. 75

With the parts so positioned, the blade cannot become detached from the standard, and will be held rigidly thereto.

Pivoted adjacent its lower end between 85 the ribs 6 is a bar 11, which constitutes a lever for holding the lugs 9 properly locked to the standard. The pivots 12 for this lever are disposed between the spaced openings 7 in the standard, and the lever is provided with upper and lower cam faces 13 and 14 respectively. It will be observed that the upper cam face 13 extends beyond the forward edge of the lever a greater distance than the lower cam face 14, and it will 90 be further observed that the said cams are of different inclinations. 95

When the shovel 8 is first applied to the standard, and the lugs are engaged with the standard at the lower ends of the apertures, 100

inward swinging movement of the lever 11 will cause the upper cam 13 to engage with the lower edge of the lug 9, and continued inward swinging movement of the said lever will cause the lug to be forced upwardly. This upward movement of the lug continues until the lever has been moved to the limit of its forward movement, whereupon the angularly bent portions of the lugs 9 and 10 will be firmly engaged with the rear face of the blade adjacent the openings 7. The lever may be locked in this position by a bail 15 slidably mounted upon the standard. When it is desired to remove the blade, the bail 15 is disengaged from the lever 11, and the latter is swung downwardly. This downward swinging movement of the lever causes the cam face 14 to engage the rounded outer end of the lower lug 9, and the latter will be forced downwardly. This movement of the blade continues until the lugs reach the bottom of the slots or apertures 7, whereupon the blade may be readily detached from the standard. It is thus seen that the upward and downward sliding movements of the blade 8 are positively controlled by the lever, and it is obvious, therefore, that the application of the blade to the standard, as well as the removal of the same therefrom, is greatly facilitated. The lever holds the blade firmly locked in proper position upon the standard, and accidental detachment therefrom is precluded. As the greater portion of the length of the lever 11 is inclosed on both sides by the longitudinally disposed ribs on the standard, danger of the lever being accidentally moved to releasing position is minimized.

From the foregoing it is obvious that I have provided a shovel or blade attachment which is of extremely simple and inexpensive construction, and which may be quickly and easily applied to and removed from the standard. Blades of various sizes and shapes may be used in connection with standards of this character, and more or less numbers of openings or lugs in the standard and blades respectively may be used for effecting a connection between the said elements.

While the present is a disclosure of the preferred embodiment of the invention, it is to be understood that the invention is not limited thereto, as various changes in the minor details of construction, proportion, and arrangement of parts may be resorted to if desired without departing from the spirit of the invention as defined by the appended claims.

I claim:—

1. In combination with a standard having elongated apertures therein, a blade adapted to slide upon said standard longitudi-

nally of said apertures, lugs carried by said blade engaged in said apertures, the said lugs being adapted when the blade is moved in one direction to lock said blade to said standard, and a lever for sliding said blade in either direction.

2. In combination with a standard having an aperture therein, a blade, an angular lug carried by said blade adapted to enter said aperture and to engage behind one edge thereof, and a lever pivoted on said standard and being adapted to hold said lug locked with the said edge.

3. In combination with a standard having an aperture therein, a blade, an angularly bent lug carried by and projecting from said blade and being adapted to enter said aperture, the angularly bent portion of said lug being adapted to engage behind one of the edges defining said aperture, a lever on said standard, and a cam face on said lever adapted to engage said lug to force the same into binding engagement with said opening edge.

4. In combination with a standard having a pair of apertures therein, a blade, a pair of lugs carried by said blade and being adapted to enter said apertures, a lever on said standard, and cam faces on said lever adapted to engage and move said lugs in said apertures.

5. In combination with a standard having a pair of apertures therein, a blade, a pair of lugs carried by said blade, angular extensions at the ends of said lugs, the said extensions being adapted to enter said apertures and to engage behind the edges defining the same, a lever on said standard, a cam on said lever adapted when the latter is moved in one direction to engage one of said lugs and move the same into locking engagement with said edges, and a second cam surface on said lever adapted when the latter is moved in reverse direction to engage the other of said lugs to withdraw the same from engagement with said opening edge.

6. In combination with a standard having a pair of apertures therein, a blade, a pair of lugs carried by said blade, angular extensions at the ends of said lugs, the said extensions being adapted to enter said apertures and to engage behind the edges defining the same, a lever pivoted on said standard between said openings, cam faces on said lever arranged one on each side of the pivot thereof, one of the said cams being adapted when the lever is moved in one direction to engage one of said lugs to move the same into locking engagement with the said edges, and the other of said cam faces being adapted when the lever is moved in the opposite direction to engage the other of said lugs and to move the same from locking engagement with the said edges.

7. In a device of the class described, a standard having longitudinally alined spaced apertures therein, a blade, angularly disposed lugs carried by and projecting 5 rearwardly from the said blade and being adapted to enter said apertures and to engage behind the edges defining the same, a lever pivoted to said standard and being capable of reciprocating said blade on said standard, and means for locking said lever 10 against movement.

In testimony whereof I affix my signature in presence of two witnesses.

FRANK C. KIRKPATRICK.
